United States Patent Office

Des. 196,748
Patented Oct. 29, 1963

196,748

GAUGE

Jesse P. Shanok and Victor Shanok, both of
863 65th St., Brooklyn, N.Y.

Filed Jan. 8, 1962, Ser. No. 68,221

Term of patent 14 years

(Cl. D52—6)

FIG. 1

FIG. 2

FIG. 3

FIG. 4

FIG. 5

FIGURE 1 is a front elevational view of a gauge showing our new design;

FIGURE 2 is a side elevational view thereof;

FIGURE 3 is a top plan view thereof;

FIGURE 4 is a rear elevational view thereof; and

FIGURE 5 is a bottom view thereof.

The essential features of the design are shown in full lines.

We claim:

The ornamental design for a gauge, substantially as shown and described.
